UNITED STATES PATENT OFFICE.

MINNIE SHAW, OF CHICAGO, ILLINOIS.

CORSET.

1,247,019.

Specification of Letters Patent. Patented Nov. 20, 1917.

Application filed April 20, 1916. Serial No. 92,395.

To all whom it may concern:

Be it known that I, MINNIE SHAW, a citizen of the United States, and a resident of the city of Chicago, county of Cook, and 5 State of Illinois, have invented certain new and useful Improvements in Corsets, of which the following is a specification.

My invention relates to improvements in corsets and has for its object the production 10 of a corset which will afford ease and comfort to the wearer and which will provide a smooth, even surface for engagement with outer garments of the wearer.

A further object is the production of a 15 corset which will be of durable and economical construction and which may be readily and expeditiously applied in the employment of the corset.

Other objects will appear hereinafter.

20 The invention consists in the combinations and arrangements of parts hereinafter described and claimed.

The invention will be best understood by reference to the accompanying drawing 25 forming a part of this specification, and in which the figure is a perspective view of a corset embodying the invention.

The preferred form of construction, as 30 illustrated in the drawing comprises a corset 1 which in general construction is conventional. The corset is provided, as is usual, with an opening 2 at its rearward side extending the entire length of the corset, which opening is spanned by lacings 3 35 whereby the width of said opening may be varied to tighten or loosen the corset as will be readily understood.

Provided upon the outer side of the corset at the back of the same is a covering element 4 adapted, when in operative position, 40 to cover the opening 2. Said element 4 comprises a central body portion of elastic material which is reinforced at its longitudinal edges by strips 5 and 6 of non-elastic material which embrace said edges, being 45 secured thereto by the stitching. One edge of the covering element 4 is permanently secured by stitching 7 to the body of the corset at one side of opening 2, said stitching 50 7 passing through the edging strip 5. The opposite edge of said covering element is releasably secured to the corset by means of a plurality of hooks 8 spaced along the free edge of said covering element at the 55 under-side thereof, said hooks 8 being fas-

tened to the edging strip 6. The hooks 8 are adapted to engage with either of two spaced rows of eyes 9 and 10 which are provided upon the corset 1 at the opposite side of opening 2. The eyes 9 are attached 60 to a supplemental strip 11 provided upon the corset which strip is adapted to loosely engage over the eyelets of the corset at the corresponding side of opening 2 which are engaged by lacings 3 as will be readily 65 understood. Two spaced rows of eyes are provided to allow for a wide range of adjustment in the corset, that is in the width in the opening 2 without rendering the covering member 4 inoperative. The elasticity 70 of the covering member of course compensates for lesser adjustments in the width of opening 2.

With the construction set forth it will be seen that at all times the opening 2 will be 75 completely closed by the covering or closing member, and because of the elasticity thereof and the adjustment afforded by the provision of a plurality of rows of eyes for engagement with the hooks provided upon 80 the covering member, said covering member will remain in snug engagement over the lacings 3 and against the body of the wearer. Such a closing member serves to protect and reinforce the back or spine of the wearer 85 and thus to conduce to the ease and comfort of the wearer. The covering or closing member may be attached to any corset already in use or may be made a part of a corset in the course of manufacture of the 90 same.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 95 100 the appended claim.

Having described my invention what I claim as new and desire to secure by Letters Patent is:

A corset having the usual adjacent edges 105 and lacings connecting the same forming an opening of variable width co-extensive in length with the corset; a covering element of elastic material arranged at the outer side of the corset for covering said 110

opening, said element having one edge permanently fastened to the corset at one side of said opening; means for releasably fastening the opposite edge of said element to the corset at the opposite side of said opening, said means comprising a row of engaging devices provided upon said last mentioned edge of said element; and a plurality of spaced rows of coöperating engaging devices provided upon the corset for engage-

ment by said first mentioned engaging devices, substantially as described.

In testimony whereof I have signed my name to this specification in the presence of two subscribing witnesses.

MINNIE SHAW.
